United States Patent Office

Des. 195,335
Patented June 4, 1963

195,335

TILE

Donald R. Speaker, North Hollywood, Calif., assignor to Pomona Tile Manufacturing Company, Los Angeles,
Calif., a corporation of California

Filed July 12, 1962, Ser. No. 70,894

Term of patent 14 years

(Cl. D18—2)

FIG. 1.

FIG. 2.

FIG. 3.

FIG. 4.

6

FIG. 5.

FIG. 6.

The undisclosed rear is substantially plain.

I claim:

The ornamental design for a tile substantially as shown and described.
